UNITED STATES PATENT OFFICE

158,426

IRON HOLDER

Everette L. Wilson, Kansas City, Mo.

Application August 4, 1949, Serial No. 4,288

Term of patent 3½ years

(Cl. D49—6)

To all whom it may concern:

Be it known that I, Everette L. Wilson, a citizen of the United States, residing at 2334 Quincy Street, Kansas City, in the county of Jackson and State of Missouri, have invented a new, original, and ornamental Design for an Iron Holder, of which the following is a specification, reference being had to the accompanying drawing, forming a part thereof.

Figure 1 is a perspective view of an iron holder, showing my new design.

Fig. 2 is a top plan view thereof;

Fig. 3 is an end elevational view thereof; and
Fig. 4 is a side elevational view thereof.

I claim:

The ornamental design for an iron holder, as shown.

EVERETTE L. WILSON.
